(57) **CLAIM**

The ornamental design for an ottoman as shown and described.

DESCRIPTION

FIG. 1 is a perspective view of an ottoman according to our new design.

FIG. 2 is a front view of the ottoman of FIG. 1.

FIG. 3 is a rear view of the ottoman of FIG. 1.

FIG. 4 is a left side view of the ottoman of FIG. 1.

FIG. 5 is a right side view of the ottoman of FIG. 1.

FIG. 6 is a top view of the ottoman of FIG. 1; and,

FIG. 7 is a bottom view of the ottoman of FIG. 1.

The broken lines depict portions of the ottoman that form no part of the claimed design.
